UNITED STATES PATENT OFFICE.

RODERICK WEIR, OF WINNIPEG, MANITOBA, CANADA.

CLOTHES-WARDROBE.

No. 852,862

Specification of Letters Patent.

Patented May 7, 1907.

Application filed May 16, 1906. Serial No. 317,096.

To all whom it may concern:

Be it known that I, RODERICK WEIR, a subject of the King of Great Britain, residing at Winnipeg, in the county of Selkirk, Province of Manitoba, Canada, have invented certain new and useful Improvements in Clothes-Wardrobes, of which the following is a specification.

My invention relates to improvements in clothes wardrobes; and the objects of the invention are to devise certain changes to perfect the construction and increase the advantages over my invention shown and described in my United States Patents, numbers 749,126, dated January 5, 1904; and 724,977, dated April 7, 1903, respectively; in which I have shown my inventions as a means for displaying clothing; and in this particular device I provide a means by which a number of trousers may be suspended in uniform position, and contained within the wardrobe, and be withdrawn therefrom for removal or examination.

My invention consists of a suitable rack provided with a series of removal hangers, and is also adapted to be withdrawn from the interior of the wardrobe and turned up to further facilitate the displaying of the garments.

The hangers will be arranged on the rack that any one may be removed without interfering with the remaining hangers.

I attain these objects by the device as illustrated in the accompanying drawings, in which

Figure 1 is a perspective view of a wardrobe showing the garment rack arranged within; Fig. 2 is a perspective view showing the rack withdrawn; Fig. 3 is a perspective view of the rack turned up; Fig. 4 is a perspective view of one of the hangers; and Fig. 5 is a cross section view through the rack.

Like letters refer to like parts throughout the drawings and specifications.

a represents the cabinet of the wardrobe, consisting of sides, back, top and bottom; the front being provided with a door *b* adapted to open up the lower half of the cabinet, and arranged to lower down and slide away into the interior; and a door *c* adapted to slide up and open the upper half of the cabinet. Fastened to the sides on the interior of the cabinet are blocks or brackets *d* adapted to support the ends of the carrying bars *e*, of a supporting rack *f*. The rack *f* consists of

two side bars *g*, provided with a longitudinal groove *h*, extending the entire length of the bars. The bars *g* forming the sides of the rack are made fast in parallel relation to the underside of the carrying bars *e*. 60

Slidably carried in the rack *f* is an extension rack *i*. The side bars *j* of the rack *i*, are formed with a flange *k*, adapted to engage in the groove *h*. The rack *i* is adapted to be extended in a forward direction from the front end of the rack *f*, and is provided with a cross bar *l*, to be used as a handle by which it may be slid outward and inward; and also as a brace to maintain the front ends of the side bars *j* together. Formed and extending inward from each of the side bars *j* of the rack *i*, are flanges *m*, and formed on the top faces of each of the flanges *m*, is a rib *n*. 70

Hinged to the back end of the rack *i*, by hinges *o*, is a frame *p*, adapted to slide in the grooves *h* of the rack *f*, in combination with the rack *i*. The frame *p* is for the purpose of supporting the rack *i* in the rack *g*, when it is desired to turn the rack *i* up to display the garments to a better advantage; as it is fully 75 80 illustrated in Fig. 3. Pivotaly connected to supporting bars *q* extending forward from the frame *p*, is an adjusting bar *r*. The adjusting bar *r* is formed with an arm *s* extending at right angles at each end; the ends of the arms *s* being adapted to engage in any one of a series of notches *t*, formed in the underside of the side bars *j* of the rack *i*, and maintain the rack *i* in a turned up position, that the garments may be advantageously 85 90 displayed for examination.

Carried on the rack *i* are a series of removable hangers *u*, such as is shown in Fig. 4 of the drawings. The hangers *u* are formed that the center part provides a bar on which the trousers may be hung, and at each end of the bar is a square shaped end *v*, and formed in the underside of each of the ends *v*, is a groove *w*, adapted to engage with the rib *n*, formed on the top face of the flange *m*. 95 100

x represents hinged and inwardly folding bars attached to the sides of the rack *i*; and having a downwardly projecting notched flange *y*, each of the notches *z*, adapted to engage over one of the hangers *u*, and maintain them in their proper intervals, and also to hold them in place on the rack *i*, when the rack is turned up. 105

Formed in the top face of each of the ends *v* of the hangers *u*, is a pocket *1* adapted to 110

contain a price or size ticket 2. One end will be preferably used for the price ticket and the opposite end for the size ticket.

When it is desired to remove any pair of trousers from the rack, the hinged bars x are turned up, and the hanger u containing the particular pair of trousers to be removed is lifted from off the rack i ; and when it is desired to replace any hanger with or without a pair of trousers attached, it will be slipped on from the front end of the rack, and the remaining hangers on the rack will be pushed up to close the gap made by the removed hanger, so that the hangers will always maintain their proper position on the rack. By folding in the hinged bars x again, the hangers will be held in position with the rack that it may be turned up without allowing any of the hangers from becoming misplaced.

Attached to the hanger bars u are supplementary hangers u' , on which may be hung a smaller size of trouser or waistcoat.

The upper half of the cabinet is adapted to be fitted with a device on which may be hung coats or waistcoats, or for any other suitable purpose.

It will be distinctly understood that this means of displaying trousers may be arranged in any suitable cabinet, counter, or silent salesman.

Slight modifications may be made in the construction and attachment of the several parts without deviating from the nature of my invention.

35 What I claim as new and desire to secure by Letters Patent is—

1. In a clothes wardrobe, the combination with the interior of a cabinet, of a series of brackets fastened to the sides of said cabinet, a supporting rack having carrying arms engaging with the said brackets, an extension rack slidably engaging with said supporting rack, inwardly extending flanges formed with the sides of said extension rack, ribs formed on the upper faces of said flanges, a series of hangers removably mounted on the said flanges, a groove formed in the under face of the ends of said hangers, said groove adapted to engage with the said rib, inwardly folding bars fastened to the sides of said extension rack, said bars having notched edges adapted to engage with the said hangers, substantially as described.

2. In a clothes wardrobe, the combination with the interior of a cabinet, of a series of brackets fastened to the sides of said cabinet, a supporting rack having carrying arms engaging with said brackets, an extension rack slidably engaging with said supporting rack, flanges formed on the inner sides of said ex-

tension rack, ribs formed on the top faces of the said flanges, a series of hangers removably mounted on said flanges, grooves formed in the under faces of said hangers, said grooves adapted to engage with the said ribs, inward folding bars hinged with the sides of said extension rack, said bars having notches formed along their inner edges, said notches adapted to engage with said hangers, a frame hinged to the inner end of said extension rack, and a cross bar fastened across the front ends of said extension rack, substantially as described.

3. In a clothes wardrobe, the combination with the interior of a cabinet, of a series of brackets fastened to the sides of said cabinet, a supporting rack having carrying arms engaging with the said brackets, an extension rack slidably engaging in grooves formed in the side bars of the said supporting rack, flanges formed on the side bars of the said extension rack, a series of hangers removably mounted on the said flanges, a frame hinged to the inner end of said extension rack, said frame adapted to slide in said supporting rack, inwardly folding bars hinged to the sides of said extension rack, said bars having notched edges adapted to engage with the said hangers, an adjusting bar pivotally connected with the said supporting rack, arms formed on the ends of said adjusting bar, said arms adapted to engage in notches formed in the underside of the side bars of said extension rack, substantially as described.

4. In a clothes wardrobe, the combination with the interior of a cabinet, of a suitable supporting rack supported therein, of an extension rack slidably engaging in said supporting rack, a frame hinged to the inner end of said extension rack, a series of hangers removably extending across the said extension rack, pockets formed in the ends of said hangers, marking tickets contained in the said pockets, hinged side bars engaging the top faces of the said hangers, an adjusting bar pivotally connected with the said supporting rack, arms extending from the said adjusting bar, said arms adapted to engage with notches formed in the underside of the side bars of the extension rack, said adjusting bar adapted to support the extension rack in an inclined position with the said supporting rack, substantially as described.

Signed at Toronto, this 14th day of May, 1906.

RODERICK WEIR.
